US0D1074354S

(12) **United States Design Patent** (10) **Patent No.:** **US D1,074,354 S**
(45) **Date of Patent:** **** May 13, 2025**

(54) **WEEDER**

(71) Applicant: **Wanqiang Chen**, Longyan (CN)

(72) Inventor: **Wanqiang Chen**, Longyan (CN)

(**) Term: **15 Years**

(21) Appl. No.: **29/943,367**

(22) Filed: **May 21, 2024**

(51) LOC (15) Cl. **08-01**

(52) U.S. Cl.

USPC **D8/11**

(58) **Field of Classification Search**

USPC **D8/7, 9, 10, 11, 12**

CPC **A01B 1/06; A01B 1/08; A01B 1/10; A01B**

1/12; A01B 1/14; A01B 1/16; B26B 3/06

See application file for complete search history.
